UNITED STATES PATENT OFFICE

2,058,450

APPARATUS FOR ANNEALING

Albert W. Herman, Cleveland, Ohio, assignor to
Lee Wilson, Cleveland, Ohio

Application March 15, 1935, Serial No. 11,235

9 Claims. (Cl. 266—5)

My invention relates to the art of annealing and, in particular, to the annealing of thin sheet metal in the form of strip or sheets.

It has now become quite common to anneal strip coils or sheets by disposing them on a base, covering them with a metallic inner cover, and lowering thereover a refractory-lined furnace bell or outer cover having a heating means therein. An example of this apparatus and method is disclosed in United States Patent No. 1,952,402, granted March 27, 1934, to Lee Wilson, except that the inner cover is not shown. The inner covers are subject to distortion and warpage in use because of the fact that they are repeatedly heated to relatively high temperatures, and then cooled, in the conventional annealing cycle. Various expedients have been employed to prevent this distortion or warpage but none of these, so far as I am aware, have been successful. Reinforcing frames have been incorporated in some inner covers but these are of little value because the frames themselves warp and lose their original shape.

I have invented a method and apparatus for eliminating or retarding warpage of the inner covers used with furnace bells of the type mentioned in the aforementioned Wilson patent. In accordance with my invention, I provide movable bracing or supporting members on the interior of the furnace cover and operable, preferably from without the furnace, into or out of engagement with the inner cover, to afford lateral support and bracing therefor during the heating portion of the annealing cycle. The inner cover must be made of relatively thin sheet metal in order to permit rapid transmission of heat to the material to be annealed, which is enclosed thereby. This requirement, of course, tends to prevent the covers from being made strong enough to be entirely self-supporting, particularly at elevated temperatures. This, I believe, is the principal cause of the warpage and distortion referred to. My invention permits the inner covers to be braced laterally when heated, without materially affecting the transmission of heat from the exterior of the cover to the interior therein. It is also useful for straightening covers which have become warped in use.

For a complete understanding of the invention, reference is made to the accompanying drawing illustrating a present preferred embodiment, although it will be understood that changes in the construction and practice there indicated may be made within the scope of my broader claims.

55 The single figure of the drawing is a transverse

sectional view showing a furnace generally of the type disclosed in the Wilson patent, having the invention incorporated therein.

Referring now in detail to the drawing, an annealing furnace 10 comprises a base 11 including a refractory hearth 12 supported on a structural framework 13. The hearth has a plate 14 providing a surface to receive the material to be annealed. The furnace 10 also includes a cover or bell 15 including side walls 16, end walls 17, 10 and a roof 18 all assembled within a suitable enclosure indicated generally at 19.

The side walls 16 of the outer cover or furnace bell are provided with heat-radiating tubes 20 having suitable burners (not shown) and exhaust 15 stacks 21, as disclosed more fully and claimed in copending application Serial No. 7,905 of Lee Wilson, filed February 23, 1935. Each of the side walls is provided with a plurality of the tubes 20 and they are spaced uniformly therealong. 20

A depending flange 22 at the lower edge of the side and end walls of the cover extends into a fluid seal provided by a channel 23 disposed along the sides and ends of the base 11. A similar channel 24 extends around the plate 14 and is 25 filled with sand to seal the joint between the base 11 and an inner cover 25. The cover 25 consists simply of an open-bottomed box formed of metallic plate, the lower edges of which enter the sand-filled channel 24. The material to be annealed is indicated as a stack of sheets 26 resting on the plate 14. The normal sequence of operations, of course, is to pile the sheets on the plate 14, place the cover 25 over them, and finally lower the furnace bell or outer cover into position 30 35 on the base.

In order to limit or retard distortion of the inner cover 25, and particularly the side walls thereof, I provide bracing bars 27 adapted to be moved into engagement with the side walls of the cover 25 during the heating portion of the annealing cycle. The bars 27 are shown vertical but may be disposed in any convenient manner and it will be understood that I provide a plurality of them on each side of the furnace, depending on the 40 length thereof, to brace the side walls of the annealing cover at appropriately spaced points. The bars 27 are carried on slide rods 28 extending through the side walls of the furnace between adjacent tubes 20. For this purpose, the side 45 walls have holes 29 and seals 30.

The bracing bars 27 may be operated through the slide rods 28 in any convenient manner but I prefer to employ hand levers 31 pivoted to the slide rods as the latter are to the bars 27, the 50 55

levers 31 being pivoted at 32 to a fixed bearing carried by the enclosure for the outer cover. The ends of the levers 31 remote from their connection with the rods 28 are preferably provided with 5 pawls 33 adapted to cooperate with curved ratchet plates 34 attached to the exterior of the furnace bell. The pawls of the upper levers 31 have counterweights 35 which normally hold the pawls in engagement with the teeth of the ratchet 10 plates. The pawls of the lower levers are normally held in such engagement by their own weight and have tips 36 by which the pawls may be manually held out of engagement when it is desired to release the levers and withdraw the 15 bars 27. The counterweights 35 of the pawls of the upper levers may be similarly lifted for this purpose.

The operation of the structure described hereinabove will doubtless be apparent from what 20 has been said. The bars 27 are normally retracted, as shown in the drawing on the left side of the furnace. When the outer cover or furnace bell has been lowered into the position shown, the levers 31 are manually pushed in 25 carrying the guide bars 27 to the position shown on the right in the drawing. When all the levers have been pushed home, the inner cover is tightly secured therebetween and braced laterally against deformation or warpage of the walls thereof.

30 When the furnace bell is to be removed, the levers 31 are released and the bracing bars 27 retracted.

It will be apparent from the above description that the invention provides novel and highly useful means for limiting or preventing distortion 35 and warping of inner covers, with the result that their useful life is considerably extended over previous practice, and the total cost of annealing thereby materially reduced. The invention is useful not only in preventing or limiting warpage of the walls of the inner covers but also 40 may be employed to straighten warped covers when they have been heated in the normal operation of the furnace, to the proper temperature. While the invention has been shown as applied particularly to the side walls of the furnace, it 45 may also be applied to the end walls with equal facility. The furnace bell or outer cover is rigidly constructed and the invention described herein makes it possible to employ the rigidity of the outer cover to support the inner cover which, as 50 stated, must necessarily be of light construction in order to transmit heat rapidly and, therefore, has little inherent strength or rigidity of its own. The bracing means, in addition to being applied to the side walls and ends of the furnace bell, may 55 also be provided in the roof or the base. The invention is applicable, furthermore, not only to annealing furnaces of the type shown in the Wilson patent, but also to stationary furnaces adapted to receive annealing boxes, and any other 60 type of furnaces wherein the same problem is presented.

If it is desired to provide an outward force for bracing the inner covers, the bars 27 may be replaced by hooks on the rods 28, adapted to engage eyes on the inner cover. By this means an outward force may be exerted on the covers 5 where desirable.

Although I have described and illustrated herein in but one preferred form and practice of the invention, it will be apparent that numerous changes therein may be made without departing 10 from the spirit of the invention or the scope of the appended claims.

I claim:

1. Annealing apparatus comprising a furnace, slide rods extending through the furnace wall, and bracing bars carried on the slide rods for engaging and laterally supporting a cover within the furnace enclosing the material to be annealed. 15

2. The apparatus defined by claim 1 characterized by means operable from the exterior of the 20 furnace for actuating the bars.

3. The combination with an annealing furnace of a plurality of bracing bars movably carried on the interior thereof adapted to engage and laterally support an enclosure for the material being 25 annealed, of means operable from without the furnace for retracting and advancing said bars.

4. In an annealing furnace, slide rods movably mounted in a wall thereof, and a bracing bar carried on said rods for engaging an enclosure 30 within the furnace for the material to be treated.

5. The apparatus defined by claim 4 characterized by levers mounted exteriorly of the furnace for operating said rods.

6. The apparatus defined by claim 4 characterized by levers mounted exteriorly of the furnace for operating said rods, and means for locking said levers in operated position. 35

7. Annealing apparatus comprising a furnace having a hearth adapted to support the material 40 to be annealed, a cover adapted to be disposed within the furnace over said material and on said hearth, said cover having a side wall and a top, and means carried by the furnace and extending inwardly therefrom for applying pressure 45 to said side wall.

8. Annealing apparatus comprising a furnace having a hearth, side walls and a roof, an enclosure for the material to be annealed having a side wall and a top and adapted to be disposed 50 within the furnace on said hearth, and means slidable through the side walls of the furnace and engaging said side wall of the enclosure to provide lateral support for the latter.

9. Annealing apparatus comprising a furnace having a cover and a hearth adapted to receive material to be annealed, movable means extending inwardly from the furnace for supporting the cover disposed over the material, and means for operating said movable means from the exterior 55 of the furnace. 60

ALBERT W. HERMAN.
